UNITED STATES PATENT OFFICE.

GUSTAVIUS GUINAND, OF LOS ANGELES, CALIFORNIA.

VALVE-SPRING LIFTER.

1,352,407.

Specification of Letters Patent. Patented Sept. 7, 1920.

Application filed December 11, 1919. Serial No. 344,169.

To all whom it may concern:

Be it known that I, GUSTAVIUS GUINAND, a citizen of the United States, residing at Los Angeles, in the county of Los Angeles 5 and State of California, have invented new and useful Improvements in Valve-Spring Lifters, of which the following is a specification.

This invention relates to a device for 10 facilitating the removal of the spring seat supporting pins of internal combustion engine valve stems, and has for its object to provide a jack that may be readily applied with facility to enable the removal of the 15 pins in various constructions of internal combustion motors, it being a further object of the invention to provide a lifting device or jack that has its parts so constructed that they may be easily rearranged or connected 20 as the exigency with relation to the construction of the motor may determine.

With these and other objects in view the invention consists of the construction and details an embodiment of which is illustrated in the accompanying drawings and described and claimed herein.

Figure 1 is a plan view of the improved spring lifting jack in one organization of its parts.

Fig. 2 is a side elevation of the jack shown in Fig. 1, parts being broken away for clarity and showing the device in one application.

Fig. 3 is a sectional view on line 3—3 35 of Fig. 2.

Fig. 4 is a side elevation of the lifting jack showing its parts rearranged to enable it to be used as an extended lever for lifting the spring collar from its supporting 40 pin.

Fig. 5 is a side elevation of the lifting device showing still another mode of use.

In Figs. 1 to 3 the lifting jack is illustrated in one assembly or organization of 45 the parts in which a base forming member in the form of an elongated plate 2 is shown, one end of the plate being extended in the form of a bifurcated tongue 3 to be straddled over or rested upon any convenient 50 portion as the boss 4 of an internal combustion engine having a valve rod 5 with an actuating spring 6 normally pressing downwardly on a spring collar 7 which in its lowermost position is supported by a

removable pin 8 passing through the valve 55 stem 5.

The central portion of the base member 2 is longitudinally slotted as at 2' and in the slot there is rotatively mounted an eccentric cam 10 that is secured on a transverse shaft 60 11 journaled in suitable bearings 12 formed on or attached to the sides of the base member 2, this shaft preferably being provided with a universal joint 13 from which extends a handle or shaft section 14 that may 65 be provided with a cross bar 15, whereby the operator may readily rotate the cam shaft 11 from a position in which the shaft section 14 is angularly disposed with relation to the axis of the cam shaft 11 thereby 70 enabling the ready and efficient use of the device in engines of various types of construction, and in which it would be desirable to enable the mechanic to operate the lifting jack through means of a flexible 75 shaft.

The eccentric cam 10 is shown as engaging a roller 16 mounted on a shaft 17 that is disposed transversely across a frame 18 or hollow structure lever the rear end of 80 which has a hub portion 19 through which extends a pivot pin 20 preferably rigidly mounted in the hub 19, the projecting ends of the pivot pin being adapted to slide freely into and be removable from a pair 85 of bearing ears 21 that are slotted as at 22 on their front edges to permit the free insertion and removal of the pivot pin 20 on which there is preferably mounted a pivot 90 bail 23, the transverse bar of which straddles the bearing ears 21 and is adapted to be turned downwardly to an interlocking position as shown in Fig. 2 so as to prevent undesirable or accidental removal or play 95 of the lever member 18 and yet permit the entire removal of the latter by swinging the bail 23 to an uppermost position over the top of the bearing ears 21. To facilitate this movement of the bail 23 it may be provided with a slight or suitable nog 24 projecting outwardly from its transverse or bow part.

Preferably the cam 10 and its complementary roller 16 are provided with inter-engaging guide means to secure perfect 105 tracking of these members and prevent lateral play, and as shown in Fig. 3 the cam is provided with a transversely concave

groove 10' in which runs a complementary peripheral convex bead 16' on the roller 16.

The end of the lever 18 that is disposed above the bifurcated tongue 3 of the base member is provided with a rocking chair 25 that is centrally slotted as at 26 to be readily passed around the stem 5 of the valve and to engage under the lower surface of the spring collar 7, clearly shown in Fig. 2, the chair having diametrically opposite pivots 27 in the arcuate ends 18' of the lever 18; the chair 25 being pivotally mounted so that it will remain in parallel position to the lower edge of the collar 7 while the latter is being lifted irrespective of the angular movement of the lifting lever 18 when it is actuated by the lifting cam 10; and one of the objects of providing the slotted bearing ears 21 is to provide for a slight to and fro movement of the pivot 20 in the slots 22 so that the lever 18 may follow, somewhat, the upward movement in a vertical plane of the chair 25 while it is engaging the collar 7.

For the purpose of automatically locking the lifting lever 18 at successive steps or stages as it is lifted by the cam 10, a suitable latch or detent device is provided and is adapted to automatically snap into locking engagement with one or the other of the parts while it is carried by the other part. In this case a latch 28 is provided with a removable pivot or pin 29 that can be adjusted into one or another of the apertures 30 provided in the hollow lever member 18, this pin also being adjustable in one or another of a series of apertures 31 provided in the shank of the latch 28.

One edge of the latch is slotted or serrated as at 32 and the lower and serrated end of this latch is normally thrown outwardly to engage the adjacent end wall of the slot 2' in the base member 2 and at the back of the tongue 3 by means of a contractile spring 33 that may be hooked removably into one or another of the apertures 31 in the latch member, and has its opposite end hooked into an ear or otherwise suitably connected to an upstanding bow 34 here shown in the form of a U-shaped member straddling the parallel sides of the lifting lever 18.

From the above it will be seen that when the mechanic desires to remove the spring supporting pin 8 from the valve stem 5 the improved tool will be applied to the supporting part as 4 below the spring collar 7 and the flexible shaft 11-14 so disposed that the cam 10 will be swung down to permit the lever 18 to lie substantially parallel to the base member 2 at which time the latch 28 will have been projected downwardly through the slot 2' but thrown with its lower portion into contact with the end wall of the slot by the reaction of the spring 33.

The mechanic adjusts the chair 25 under

the collar 7 and then by turning the flexible shaft 11-14 in either direction causes the lever 18 to tilt upwardly on its fulcrum 20 and thus lift the spring collar 7 and compress the spring 6, meanwhile the latch 28 automatically clicks into interlocking position at its several teeth 32 so that the collar is automatically locked at successive stages against downward movement. It is obvious that as soon as the valve collar has been lifted to the desired extent the pin 8 can then be readily withdrawn.

Cases may be encountered where it is not convenient to utilize the tool when it is organized as shown in Figs. 1 and 2, and I have therefore provided for the rearrangement of the base member 2 and the lever 18 so that a form of extended simple lever can be secured, this being plainly illustrated in Fig. 4, wherein the lever 18 is shown as pivoted in the reverse position in the slotted ears 21 instead of in the position shown in Fig. 2, so that the lever 18 extends in the opposite direction and is supported against lateral swaying movement with respect to the base member 2 by means of a saddle 35 formed or provided on the end of the member 2 to encompass the side faces of the lever 18.

In this arrangement the spring 33 is disconnected from the latch 28 and the latter is inverted with respect to the lever 18 and the pin or pivot 29 passed through suitable of the aligned perforations 30-31 so that one end of the latch 28, that is provided with a yoke 28', can be set against an adjacent flange or boss 4' with the chair 25 placed into engagement with the lower and outer surface of the spring collar 7, and therefore when the extended lever organization 2-18 is pressed downwardly in the direction of the arrow, Fig. 4, the shorter arm of the lever carrying the chair 25 and tilting about the pin 29 may be readily forced upwardly to lift the collar 7 away from the pin 8 of the stem 5. It will be obvious that in this case the actuating cam 10 is not utilized.

A further mode of utilizing the tool is illustrated in Fig. 5 wherein the base member 2 and the lever 18 are shown in the extended position of Fig. 4, but the latch 28 is either entirely removed from the member 18 or is not utilized and a fulcrum for the lever is secured as by means of a knotted cable or wire 40 having a hook 41 at its upper end and any of the knots 40' of the cable being passed into a fork 42 that is provided on and extends rearwardly from the bow member 34 to which the spring 33 is attached.

It will be seen that in this case the hanger member 40 can have its hook 41 slipped over any suitable angular part as at the top of the valve head and one of the knots 40' of the cable or wire 40 passed below and into

the crotch of the fork 42 and then the outer end of the lever device can be pressed downwardly so that it will rock on the fulcrum forming knot below the fork and the chair 5 end of the lever lifted to compress the spring 6, as clearly shown, to remove the collar from the pin 8.

Various changes may be made without departing from the spirit of my invention as 10 claimed.

I claim:

1. A valve spring lifting device comprising a base member having a tongue to straddle or rest upon a supporting part, a lifting lever connected at one end to the base member and having at the other end above the tongue a yoke to take around a valve stem below the spring, a spring latch mounted on one of the parts to engage the other and support it against the load of the 20 spring, and a manually operable cam mounted upon the base member for jacking up the lever.

2. A valve spring lifting device comprising a base member having a tongue to straddle or rest upon a supporting part, a lifting lever detachably connected at one end to the base member and having at the other end above the tongue a yoke to take around a valve 25 stem below the spring, a spring latch mounted on one of the parts to engage the other and support it against the load of the spring, and a manually operable cam mounted upon the base member for jacking up the lever.

3. A valve spring lifting device comprising a base member having a tongue to straddle or rest upon a supporting part, a lifting lever slidably connected at one end to the base member and having at the other end above the tongue a yoke to take around a valve 40 stem below the spring, a spring latch mounted on one of the parts to engage the other and support it against the load of the spring, and a manually operable cam mounted upon the base member for jacking up the lever.

4. A valve spring lifting device comprising a base member having a tongue to straddle or rest upon a supporting part, a lifting lever connected at one end to the base member and having at the other end above the tongue a yoke to take around a valve 50 stem below the spring and a rocking chair 55 therein to engage the valve spring seat, a spring latch mounted on one of the parts to engage the other and support it against

the load of the spring, and a manually operable cam mounted upon the base member for jacking up the lever.

60

5. A valve spring lifting device comprising a base member having a tongue to straddle or rest upon a supporting part, a lifting lever connected at one end to the base member and having at the other end above the tongue a yoke to take around a valve 65 stem below the spring, a spring latch mounted on one of the parts to engage the other and support it against the load of the spring, a manually operable cam mounted 70 upon the base member for jacking up the lever, and a roller on the lever to engage the cam.

6. A valve spring lifting device comprising a base member having a tongue to straddle or rest upon a supporting part, a lifting lever connected at one end to the base member and having at the other end above the tongue a yoke to take around a valve 75 stem below the spring, a spring latch mounted on one of the parts to engage the other and support it against the load of the spring, a manually operable cam mounted upon the base member for jacking up the lever, and a flexible shaft extending from 80 the cam.

7. A valve spring lifting device comprising a base member having a tongue to straddle or rest upon a supporting part, a lifting lever connected at one end to the base 90 member and having at the other end above the tongue a yoke to take around a valve stem below the spring, a spring latch mounted on one of the parts to engage the other and support it against the load of the 95 spring, and a manually operable cam mounted upon the base member for jacking up the lever, the lever being reversible on the base and the latch invertible to form a truss on which the extended lever can rock.

100

8. A valve spring lifting device, comprising a base member having a tongue to straddle or rest upon a supporting part, a lifting lever connected at one end to the base member and having at the other end a 105 yoke to take around a valve stem below the spring, a spring latch mounted on one of the parts to engage the other and support it against the load of the spring, and manually operable means mounted upon the base 110 member for jacking up the lever.

In testimony whereof I have signed my name to this specification.

GUSTAVIUS GUINAND.
